Attorney

UNITED STATES PATENT OFFICE.

HARRY SELDOMRIDGE, OF CLINTON, INDIANA.

SUSPENDING DEVICE FOR TOOLS AND THE LIKE.

1,392,530.

Specification of Letters Patent.

Patented Oct. 4, 1921.

Application filed June 17, 1921. Serial No. 478,343.

To all whom it may concern:

Be it known that I, HARRY SELDOMRIDGE, a citizen of the United States of America, and resident of Clinton, in the county of Vermilion and State of Indiana, have invented certain new and useful Improvements in Suspending Devices for Tools and the like, of which the following is a specification.

This invention relates to hangers or supports, and more particularly to a device intended for adjustably supporting loads at different heights with respect to an operator, or at least this is the primary object of the invention, but the inventor does not wish to be limited, of course, with respect to the particular feature.

An object of this invention furthermore is to produce a hanger having a counter balancing weight, associated with means for permitting the elevating or lowering of the hanger, the said device being associated with means for holding the parts at different positions of adjustment until manually controlled or operated.

This device is primarily intended for use in connection with the support of electric hair cutting devices and other implements employed by barbers, the device being intended to suspend the implements above the head clearance in a room and operative to be manipulated by a barber for drawing the suspending means down for the convenient removal of the implements carried by the suspending means; and the said invention furthermore contemplates the provision of a flexible element adapted to run over a pulley, one end of which flexible element has a counter weight, and the said flexible element having a friction device which will prevent the free running of the flexible member over the pulley, said friction device preferably being of such a nature as to overcome the gravity of the weight, but capable of freeing the flexible member and permitting it to move through the guide or friction element when manipulated.

A still further object of this invention is to produce a flexible element of the character indicated, associated with a stop or check which limits the movement of the weight upwardly and having the characteristics of retaining the parts frictionally as heretofore indicated.

With the foregoing and other objects in view, the invention consists in the details of

construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of a device embodying the invention;

Fig. 2 illustrates an enlarged detailed view thereof; at a position at right angles to that shown in Fig. 1; and

Fig. 3 illustrates a sectional view on the line 3—3 of Fig. 2.

In these drawings 5 denotes a weight, preferably having an aperture 6 therethrough, constituting a guide for the flexible element 7 which may be preferably in the nature of a cable having a looped portion operating over a hanger 8 provided with a sheave pulley 9 to permit the free running of the cable or flexible member as it is manipulated. The weight is permanently attached to one end of the cable as shown at 10, and the opposite length of cable is guided through the aperture 6 and projects below the weight.

Suitable implement supporting hooks such as 11 may be provided, the hooks, in the present embodiment of the invention, having an apertured head 12 through which the cable projects, the said head being secured to the cable by a fastening 13 such as a set screw. The shanks of the hooks are further connected by a yoke 14 forming a guide for the cable which extends below the ends of the hooks and preferably terminates in a snap hook 15 which may be used for suspending implements.

One length of the cable extends through an apertured guide or barrel 16 in which it is slid able, the said guide being offset or diagonal with relation to the perpendicular, an arrangement which causes a slight buckling of the cable, due to the weight which exerts a pull to hold the cable straight except at the station where it passes through the guide. The relation of parts is well shown in Fig. 2, and it will be seen that the free running of the cable through the guide will be prevented by the rather abrupt bend which the cable must encounter at the ends of the guide.

The guide is formed with or attached to

an anchoring clamp 17 to which the other loop of the cable is connected by fastenings 18 such as set screws, and in the present embodiment of the invention, the clamp 17 5 is tubular and has a clearance for the cable to pass through, after which the said clamp is secured to the cable and constitutes in addition to its clamping function, a stop which arrests the ascent of the weight, 10 thereby limiting the movement of the weight in one direction.

Of course the clamp may be adjusted on the cable to any desired position by reason of the removable securing devices employed 15 in connection with the clamp.

The diagonal arrangement is shown in Fig. 2 whereby that length of cable extending through the clamp extends across the guide and causes the length of cable to be 20 held well separated, so that those portions of the cable above and below the clamp and guide are maintained in parallel relation to each other.

As shown in the drawing, the weight has 25 a boss 19 which constitutes the abutment for the clamp, and this boss, of course, is apertured to form a continuation of the aperture 6 through which the cable operates.

I claim:

30 1. In a suspending means for tools and the like, a hanger, a cable operating thereover, a weight suspended from one end of the cable, a guide through which the cable is movable, the said guide being diagonal to

the perpendicular, a clamp carrying the said 35 guide and engaging the opposite run of the cable, means for securing the said clamp to the cable, the said weight having a guide formed therein, the said cable extending through the guide of the weight, and implement supporting elements on the said cable below the weight.

2. In a suspending means for tools and the like, a hanger, a cable operating thereover having parallel portions projecting 45 therebelow, a weight connected to one end of the cable, implement supporting elements connected to the cable near the opposite end, the said cable being guided by the weight, a clamp connected to one run of the cable, 50 and a guide carried by the said clamp and having an aperture to receive the opposite run of the cable, the said guide being diagonally disposed with relation to the parallel portions of the cable.

55 3. In an implement suspending device, a cable doubled on itself, means for supporting the looped portion of the cable to permit its movement, a weight connected to one end of the cable, said weight having an aperture therethrough forming a guide for the 60 said cable, implement suspending elements on the cable below the weight, a clamp connected to one run of the cable, and a friction maintaining element carried by the clamp 65 and adapted to engage the other run of the cable.

HARRY SELDOMRIDGE.
